Fig. 6

FIGURE 1 is a perspective view of a chair embodying my design, and showing a seat and casters in broken lines.

FIGURE 2 is a side elevational view of the base.

FIGURE 3 is a top plan view.

FIGURE 4 is an inverted plan view.

FIGURE 5 is a front elevational view of the base, and FIGURE 6 is a rear elevational view.

The broken line elements shown in FIGURE 1 are omitted from FIGURES 2 to 6, inclusive for the purpose of convenience of illustration.

The dominant features of my design reside in those portions shown in full lines on the drawing.

I claim:

The ornamental design for a chair, substantially as shown and described.
